(57) **CLAIM**

The ornamental design for an audio amplifier, as shown and described.

DESCRIPTION

FIG. 1 is a perspective view of an audio amplifier showing our new design;

FIG. 2 is another perspective view of the audio amplifier of FIG. 1;

FIG. 3 is another perspective view of the audio amplifier of FIG. 1;

FIG. 4 is a front view of the audio amplifier of FIG. 1;

FIG. 5 is a rear side view of the audio amplifier of FIG. 1;

FIG. 6 is a left side view of the audio amplifier of FIG. 1;

FIG. 7 is a right side view of the audio amplifier of FIG. 1;

FIG. 8 is a top view of the audio amplifier of FIG. 1; and,

FIG. 9 is a bottom view of the audio amplifier of FIG. 1.

In the drawings, the broken lines illustrate portions of the audio amplifier that form no part of the claimed design.

1 Claim, 8 Drawing Sheets
